UNITED STATES PATENT OFFICE.

WILLIAM PRELLWITZ, OF EASTON, PENNSYLVANIA, ASSIGNOR TO INGERSOLL-RAND COMPANY, OF NEW YORK, N. Y., A CORPORATION OF NEW JERSEY.

ROCK-DRILLING MACHINE.

No. 892,082.

Specification of Letters Patent.

Patented June 30, 1908.

Application filed April 17, 1906. Serial No. 312,090.

To all whom it may concern:

Be it known that I, WILLIAM PRELLWITZ, a citizen of the United States, and resident of Easton, in the county of Northampton 5 and State of Pennsylvania, have invented a new and useful Improvement in Rock-Drilling Machines, of which the following is a specification.

My invention relates to an improvement 10 in rock drilling machines and has for its object to provide means for causing an intermittent discharge of water and air through the drill steel at each stroke of the drill for thoroughly cleansing the drill hole of the 15 cuttings and also laying the dust which arises from the cutting bit of the drill steel striking the rock. Furthermore, the several parts are so constructed and arranged that only a small amount of water is used for each stroke 20 of the drill.

In the accompanying drawings, Figure 1 is a view partially in longitudinal central section and partially in side elevation of so much of a rock drilling machine as will give a 25 clear understanding of this invention, the drill piston being shown at the limit of its rearward movement, and Fig. 2 is a similar view with the drill piston shown at the limit of its forward movement, the piston also being shown rotated a quarter turn.

The cylinder is denoted by 1 and it is provided with the usual piston chamber 2 and motive fluid ducts 3, 4. The piston head is denoted by 5 and its forwardly extended rod by 6, which rod is provided with a chuck 7 at its forward end for the attachment of the hollow drill steel 8. The bore of the hollow 30 drill steel 8 is denoted by 9.

The piston rod 6 is provided with a duct 40 10 therein which, in the present instance, is formed by a hole drilled from the front end of the piston rod to a point adjacent to the piston head. This duct 10 in the piston rod 6 is provided with a port 11 opening to the 45 periphery of the said rod.

The front head is denoted by 12 and may be of any well known and approved form. This front head is provided with a sleeve 13 which surrounds the piston rod 6. This 50 sleeve has its inner wall cut away to form an inner annular space 14 and its outer wall cut away to form an outer annular space 15. These two spaces are in open communication through holes 16 thereby forming a water 55 feed chamber. The outer annular space 15

of the water feed chamber is in open communication through ducts 17 with a water inlet pipe 18 connected to any suitable source of water supply not shown herein.

By providing the outer annular space 15 60 in the sleeve 13, it will be seen that the water feed chamber is always in communication with the ducts 17 irrespective of the rotary position in which the sleeve 13 is inserted into its place within the front head. This inlet pipe 18 may be provided with a cock 19.

The piston rod is packed in the front head against leakage of air pressure and water, as follows:—The sleeve 13 at its inner end is packed by two reverse cup-leathers 20 70 engaging the periphery of the piston rod 6. The outer end of the sleeve 13 is provided with a U-shaped washer 21 whereby the inner and outer walls of the sleeve are packed. A stuffing box 22 may also be employed in 75 the front head as an additional safe-guard against the leakage of water around the piston rod.

To prevent the leakage of water at the chuck end of the piston rod, a rubber gasket 80 23 is inserted at the rear of the bushing 24, the opening in the chuck for the gasket 23 being less in diameter than the opening for the bushing 24, thus leaving a shoulder 25 against which the inner end of the bushing 85 seats.

The inner diameter of the gasket 23 is normally less than the outer diameter of the drill steel so that when the drill steel is inserted into the chuck, it will expand the 90 gasket thus making a water-tight joint at this point.

A hole 26 is bored in the chuck opposite the gasket 23 for the purpose of permitting the withdrawal of the gasket when it becomes worn out. This may be accomplished by pushing the gasket inwardly by a pin inserted into the hole 26, when the drill steel is removed and then withdrawing the gasket with a hook inserted into the end of the chuck. 100

The duct 10 in the piston rod is enlarged at the drill steel seat in the chuck, as shown at 27, for preventing the duct from becoming closed by the burring over of the mouth of the duct.

The port 11 of the duct 10 in the piston rod is so located that it will be brought alternately into open communication with the outer and inner space 15 of the water feed chamber in the front head and into open 110

communication with the piston chamber 2 in front of the piston head 5. As a result of this arrangement it will be seen that when the port 11 is in open communication with the water feed chamber in the front head, water will be fed through the duct 10 in the piston rod and the bore 9 of the hollow drill steel to the face of the drill.

As the piston head 5 is moved rearwardly 10 the port 11 is first cut off from communication with the water feed chamber in the front head and is then brought into open communication with the piston chamber. This will serve to permit the air to escape to 15 the face of the drill steel through the port 11, duct 10 and bore 9 thus forcing the water out of the hole being cut by the drill steel and also thoroughly cleansing the hole of the cuttings, the water serving also to lay any dust 20 that the drill steel may make when striking the rock.

As the port 11 is in communication with the water feed chamber for a small portion of each stroke, the amount of water used will 25 be very small. It is to be understood that the water may be furnished under the desired pressure to produce the proper result. It is also to be understood that the port 11 is in communication with the piston chamber for 30 only a small portion of each stroke as the piston head is near the limit of its rearward movement.

What I claim is:—

1. A cylinder, a front head, a hollow drill 35 steel, a water feed chamber, a separate air supply chamber, and a reciprocating drill piston having a duct therein arranged to be brought alternately into communication with the water feed chamber and the air supply 40 chamber for feeding water and air alternately to the drill steel.

2. A cylinder, its piston chamber, a front head, a water feed chamber therein, a hollow drill steel and a reciprocating drill piston having 45 a duct therein arranged to be brought alternately into communication with the water feed chamber and the piston chamber for feeding water and air alternately to the drill steel.

50 3. A cylinder, its piston chamber, a front head, a sleeve therein having inner and outer connected annular spaces forming a water feed chamber, a hollow drill steel and a re-

ciprocating drill piston having a duct therein arranged to be brought alternately into communication with the water feed chamber and piston chamber for feeding water and air alternately to the drill steel. 55

4. A cylinder, its piston chamber, a front head, a sleeve therein having a water feed 60 chamber, a hollow drill steel, a reciprocating drill piston having a duct therein arranged to be brought alternately into communication with the water feed chamber and piston chamber for feeding water and air alternately 65 to the drill steel, a packing for the piston rod at the inner end of the sleeve and a packing for the piston rod and sleeve at the outer end of the sleeve.

5. A hollow drill steel, a piston rod having 70 a duct therein communicating with the bore of the drill steel, a chuck for receiving the drill steel, a bushing and a gasket at the inner end of the bushing arranged to encircle the end of the drill steel for forming a water-tight 75 joint at the drill steel seat, the opening in the chuck for the gasket being of less diameter than the opening for the bushing, thus forming a shoulder against which the inner end of the bushing seats. 80

6. A hollow drill steel, a piston rod having a duct therein communicating with the bore of the drill steel, a chuck for receiving the drill steel and a gasket located at the drill steel seat arranged to encircle the end of the 85 drill steel to form a water tight joint, the said chuck having a transverse hole leading to the gasket for facilitating its removal from the chuck.

7. A hollow drill steel, a piston rod having a duct therein communicating with the bore of the drill steel, a chuck for receiving the drill steel, a bushing and a gasket located at the inner end of the bushing in position to 90 encircle the end of the drill steel at its seat, 95 said chuck having a transverse hole leading to the gasket for facilitating the removal of the gasket from the chuck.

In testimony, that I claim the foregoing as my invention, I have signed my name in 100 presence of two witnesses, this fourteenth day of April 1906.

WILLIAM PRELLWITZ.
